CONTAINER FOR AMMUNITION OR OTHER
IRREGULARLY SHAPED ARTICLESRobert R. Hutchison, Birmingham, Mich., as-
signor to General Motors Corporation, Detroit,
Mich., a corporation of Delaware

Application July 2, 1947, Serial No. 758,648

7 Claims. (Cl. 206—3)

1

The present invention relates to containers, and more particularly to chests or boxes for receiving ammunition for guns, although capable of use with other articles having somewhat similar irregular shapes.

In the disposition of ammunition in boxes and chests, a serious problem is presented by the irregular shape of the ammunition which is usually of much greater diameter at or near its base than at its nose. It is desirable that the ammunition be placed in regular rows within the box, and when the box is used to supply ammunition directly to a gun, it is essential that a regular disposition of the ammunition within the box is obtained so that it may be fed smoothly to the gun without becoming obstructed in its movement from the box to the gun.

An important object of the present invention is the provision of a container or chest in which ammunition or the like may be readily placed in regular rows and smoothly and easily removed therefrom.

Other objects and advantages of the invention will be apparent during the course of the following description.

In the accompanying drawings which form a part of this specification and wherein like characters of reference denote like parts throughout,

Figure 1 is a side elevation of an ammunition chest embodying the present invention,

Figure 2 is an end elevation thereof,

Figure 3 is a vertical transverse sectional view on the line 3—3 of Figure 1,

Figure 4 is a top plan view of the chest, parts being broken away,

Figure 5 is a fragmentary longitudinal sectional view on the line 5—5 of Figure 4,

Figure 6 is a fragmentary horizontal sectional view on the line 6—6 of Figure 1,

Figure 7 is a fragmentary vertical sectional view on the line 7—7 of Figure 1, and,

Figure 8 is a detail fragmentary view, partly in section, illustrating the inoperative or folded position of one of the shelves.

In the drawings, wherein for the purpose of illustration is shown a preferred embodiment of the invention, the chest comprises front and rear side walls 10 and bottom wall 11 integrally formed and corrugated between their ends as at 12 for structural strength. The walls 10 and 11 are backed up interiorly of the chest by a wall liner 13 which does not have corrugations corresponding to corrugations 12 on the outer walls. The ends of the chest are formed by flanged outer end members 14 corrugated as at 15 and receiving the end portions of the side and bottom walls 10 and 11. An inner end wall liner 16 is disposed within each end member 14 and abuts against the ends of walls 10 and 11, being spaced a substantial distance from the main portion of the end mem-

2

bers but engaging the corrugated and recessed portions thereof. Suitable pivoted handles 17 are disposed in recessed areas near the upper portions of end members 14 and in their inoperative position shown in Figures 2 and 5 are disposed completely within their recesses.

A lid or top cover 18 is formed with depending flanges 19 and is provided with end sections 20 which are hinged at 21 to permit raising of the end sections 20 to give access to the end portions of the chest when the main or central portion of lid 18 is in closed position, as indicated in dotted lines at the left of Figure 1. The lid 18 is hinged at 22, at a point spaced below the top of the rear chest wall, to permit raising of the lid 18 with its end sections 22. Suitable latches 23 on the front side wall 10 engage hook members or the like 24 on the flanged portion 19 of the lid to fasten the lid in closed position. The latches 23 are preferably of the type which exert a downward pressure on the lid hook members to firmly hold the lid in closed position, and are preferably three in number to engage the main or central section of the lid and each end section 20, as shown in Figures 1 and 4.

Because of the irregular shape of ammunition, the inner wall liner 13 is provided at the bottom of the chest with a relatively low rib or raised corrugation 25 adjacent to, but spaced from the rear side wall of the chest. The rib 25 is adapted to engage and support the rear portions of the lower tier of ammunition to be received in the chest, and a relatively high rib or raised corrugation 26 is disposed adjacent to, but spaced from, the front side wall of the chest to support the nose ends of the projectiles in the lower tier. Because of the difference in height between the ribs 25 and 26, the ammunition in the lower tier will be supported in a horizontal position in the bottom of the chest with space between the ribs to accommodate the links or belt. However, if the next row of ammunition is placed upon the lower tier faced in the same direction, such row of ammunition will assume an inclined position in the chest, and the next succeeding row will assume a more inclined position, so that where the ammunition is linked together in belts or links it cannot be pulled smoothly out of the chest, as for feeding to an automatic gun. In order to support the tiers of ammunition above the lower tier in a horizontal position, it is proposed to provide folding shelves or supports on the front side wall of the chest to be engaged by the smaller nose ends of the ammunition, illustrated in dotted lines at 37 in Figure 7.

As illustrated in Figure 3 of the drawings, a series of vertically spaced, longitudinally extending shelves 27 are pivotally disposed on the forward side wall of the chest. The corrugations 12 on the forward wall 10 are much deeper than

those on the rear side wall, and produce horizontal, longitudinally extending channels 28 between the corrugations. Shelf supporting pivot shafts 29 are disposed within the channels 28 and are journaled in the end wall liners 16, the ends of the shafts 29 extending into the space between the end members 14 and 16 at the left end of the chest as viewed in Figure 1 and through both members 14 and 16 at the right end of the chest into recesses 30 in the right end member 14.

The portion of the chest liner 13 which extends up the front wall 10 is separated or slotted adjacent the shafts 29, as indicated at 31, to accommodate the shelves 27 which are rigidly secured to the pivot shafts 29 and extend through the slots 31. In the lowered position of the shelves shown in Figure 3, the shelves rest upon the bottom of slots 31. The portions of liner 13 immediately above the slots are offset to receive the shelves in their inoperative position so that the folded shelves will be substantially flush with the remainder of the front wall liner. The shelves 27 may be secured to the shafts 29 in any suitable manner such as welding or riveting, and are shown as turned over at their ends to form integral sleeves to snugly receive the pivot shafts.

The ends of the shafts 29 which are at the left side of Figure 1 are provided interiorly of the space between end members 14 and 16 with generally radially extending abutments or cranks 32, shown as provided with twisted or angular end portions 33 projecting beyond the ends of the shafts and provided with openings to receive the lower hooked ends of coil springs 34. The upper hooked ends of the springs engage suitable notches in flanged ears 35 secured to or preferably struck up from a flanged edge portion 16' of the end liner 16, or a separate metal strip supplied for that purpose.

By reference to Figure 7, in which the two shelves illustrated are in different positions, it will be seen that the angle of the cranks 32-33 is such that in the raised position of the shelf shown at the top of Figure 7 the lower hooked end of the spring 34 is on one side of the axis of shaft 29 while in the lowered operative position of the shelf shown at the bottom of Figure 7, the lower hooked end of the spring 34 is on the opposite side of the axis of the shaft. Consequently the tension of spring 34, in the raised position of the shelf, is exerted in a direction to firmly hold the shelf in its raised position, whereas in the lowered position of the shelf the spring tension is exerted in a direction to firmly hold the shelf in its lowered position. In moving the shelf from either position to the other, the spring tension causes the shelf to snap over to its other position as soon as the abutment 33 and hooked spring end pass over the dead center position. This movement of the spring is permitted because of the angular portion 33 of the abutment extending beyond the end of shaft 29.

The ends of shafts 29 opposite to abutments 33 and springs 34 extend through the opposite end of the chest into recesses 30 in the chest end wall, and suitable finger cranks or handles 36 are rigidly secured to the shaft ends. The recesses 30 are sufficiently large to permit movement of handles 36 from one position to the other position. The handles 36 may be used to flip the shelves from one position to the other, with the assistance of the springs 34.

The chest illustrated in the drawings has particular utility when used with belted or linked ammunition. When loading the chest, the lid

18 is raised about hinge 22 and the shelves are moved to their raised position illustrated at the top of Figure 7 and in dotted lines in Figure 3. The belted ammunition is then arranged upon the ribs 25 and 26 with the pointed nose ends of the projectiles resting on the larger rib 26. When the lower tier of ammunition is in position, the lowest shelf is flipped down to its operative position and the second tier of ammunition is arranged with the nose ends of the projectiles resting upon the shelf and with the larger base ends of the ammunition resting upon the lower tier. The next shelf is then lowered to receive the third tier, and so on until the chest is filled. The lid 18 is then closed and latched in position.

When it is desired to remove the ammunition from the chest, or to feed it to a gun, the lid 18 or one end section 20 of the lid may be unlatched and raised, and the belted ammunition led through the open top of the chest and inserted into the gun. The ammunition may then be pulled from the chest as it is used. When one tier has been removed from the chest, the shelf which supported it will be raised to its inoperative position, either manually or by pressure of the next lower tier of ammunition against its underside, assisted by the tension of shelf spring 34.

The ribs 25 and 26 and the series of movable shelves 27 support the ammunition in horizontal tiers and permit smooth and easy withdrawal of the ammunition from the chest with no danger of the ammunition being obstructed as it is withdrawn. Due to the ease with which the shelves may be moved from one position to the other, no difficulty is experienced in either loading or unloading the chest. The shelves do not project into the chest in their folded position, the abutments 32 and springs 34 are inside of the end members and cranks 36 are outside of the chest so that there are no obstructions within the chest to interfere with smooth loading or unloading of the chest.

While the preferred embodiment of the invention has been shown and described, it is to be understood that various changes in the size, shape, arrangement and selection of parts may be made without departing from the spirit of the invention or the scope of the subjoined claims.

I claim:

1. In a container of the character described having a side wall and spaced parallel end walls, said side wall being provided with a series of vertically spaced parallel longitudinally extending recesses, a shaft arranged in each recess and extending longitudinally thereof each said shaft being journaled in said end walls, one end of each shaft projecting through an end wall, a shelf fixed on each shaft and selectively movable to an operative position at an angle to said side wall and to a folded position along said wall, means to resiliently hold said shelves in either position and means fixed on the end of each shaft externally of said container to turn the shaft and thereby move the corresponding shaft between said positions.

2. In an ammunition container having a side wall, a series of spaced parallel shafts extending longitudinally of said wall and journaled for independent rotation, a shelf carried by each shaft and selectively movable therewith to an operative position at an angle to said side wall and to an inoperative position alongside said wall, means externally of said container to independently rotate said shafts, a radially projecting crank carried by each shaft at one end thereof within said

container, said crank in one position of the shelf being disposed on one side of the axis of the shaft and in the other position of the shelf being disposed on the opposite side of the axis of the shaft, and a spring connecting said crank to the container at a point on the side of the shaft diametrically opposite to the end of said crank, whereby the resilient member will urge the shaft and shelf to either of the selected shelf positions.

3. An ammunition chest for the reception of belted ammunition, said chest having bottom, side and end walls, a series of vertically spaced parallel shafts extending longitudinally of the chest in proximity to one of the side walls, said shafts being journaled in the end walls for independent rotation, a shelf secured to each shaft and selectively movable therewith between an operative position at right angles to said side wall and a folded upwardly-extending position parallel with said wall, manually operated means connected to said shafts externally of said chest to independently rotate the shafts, a radially projecting crank carried by each shaft within said chest, said crank in one position of its shelf being disposed on one side of the axis of the shaft and in the other position of the shelf being disposed on the opposite side of the axis of the shaft, and a spring connecting the end of said crank to the chest at a point on the side of the shaft diametrically opposite to the crank, whereby the resilient member will urge the shaft and its shelf to either of the selected shelf positions in response to manual turning of said shaft.

4. A chest for belted ammunition, said chest having bottom and side walls and end members connecting said bottom and side walls, at least one of said end members comprising spaced walls, one of said side walls being corrugated to provide a series of spaced longitudinally extending channels interiorly of the chest, shafts disposed in some of said channels and journaled in the end members for independent rotation, a shelf carried by each shaft and selectively movable therewith to an operative position at an angle to said side wall and to an inoperative position against said wall, manually operated means accessible from outside the chest and connected to said shafts to independently rotate the shafts, a radially projecting abutment carried by the end of each shaft and located between the walls of said double-walled end member, said abutment having an angular end portion extending beyond the end of the shaft, said abutment in one position of the shelf being disposed on one side of the axis of the shaft and in the other position of the shelf being disposed on the opposite side of the axis of the shaft, and a coil spring connected at one end to the angular portion of the abutment and at the other end to the chest at a point on the side of the shaft opposite to the abutment, whereby the coil spring will urge the shaft and its shelf to either of the shelf positions.

5. A chest for belted ammunition, said chest having bottom and side walls and end members connecting said bottom and side walls, at least one of said end members comprising spaced walls, one of said side walls being corrugated to provide a series of spaced longitudinally extending channels interiorly of the chest, shafts disposed in some of said channels and journaled in the end members for independent rotation, a shelf carried by each shaft and selectively movable

therewith to an operative position at an angle to said side wall and to an inoperative position against said wall, manually operated means accessible from outside the chest and connected to said shafts to independently rotate the shafts, a radially projecting abutment carried by the end of each shaft and located between the walls of said double-walled end member, said abutment having an angular end portion extending beyond the end of the shaft, said abutment in one position of the shelf being disposed on one side of the axis of the shaft and in the other position of the shelf being disposed on the opposite side of the axis of the shaft, and a coil spring connected at one end to the angular portion of the abutment and at the other end to the chest at a point on the side of the shaft opposite to the abutment, whereby the coil spring will urge the shaft and its shelf to either of the shelf positions, the bottom wall of the chest being provided with an elevated longitudinally extending supporting surface adjacent the channeled side wall of the chest, whereby the nose ends of ammunition arranged in said chest will be supported by said elevated surface and said shelves to maintain such ammunition in a level position within the chest.

6. In a container having a bottom, a side wall, and end walls, a shaft journaled at its ends in said end walls adjacent and parallel with said side wall, said shaft having one end projecting through one of said ends, a shelf fixed to said shaft within said container, means attached to the other end of said shaft to maintain said shelf in a first position parallel with said bottom or a second position parallel with said side wall, and manually operable means fixed to said projecting end of said shaft to move said shelf between said first and second positions.

7. A chest for storing cartridges having ends of different diameters, said chest comprising a bottom, side and end walls, said bottom having a pair of ribs adjacent the respective side walls to support the respective ends of a first layer of said cartridges, said ribs being of different heights to thereby support cartridges thereon with their axes parallel with said bottom, and a folding shelf journaled adjacent an end wall and parallel with said bottom and above said rib of greater height, said shelf when outwardly extended, supporting the ends of lesser diameter only of a second layer of cartridges so that said second layer of cartridges are in position parallel with said first layer when the ends of larger diameter of said second layer rest upon the corresponding ends of the cartridges of the first layer.
